DESIGN FOR A RADIO ANTENNA

Kurt Emde, Itasca, Ill., assignor to Zenith Radio Corporation, Chicago, Ill., a corporation of Illinois

Application December 6, 1940, Serial No. 97,120

Term of patent 14 years

To all whom it may concern:

Be it known that I, Kurt Emde, a citizen of the United States, residing at Itasca, in the county of Du Page and State of Illinois, have invented a new, original, and ornamental Design for a Radio Antenna, of which the following is a specification, reference being had to the accompanying drawing, forming part thereof.

Figure 1 is a front elevational view of a radio antenna, showing my new design.

Figure 2 is a side elevational view of the radio antenna of Figure 1.

The drawing has been shaded to show contrasting appearance. The rear of the antenna appears substantially the same as the front.

I claim:

The ornamental design for a radio antenna, as shown and described.

KURT EMDE.
